(57) **CLAIM**

The ornamental design for an aerosol delivery device as shown and described.

DESCRIPTION

FIG. 1 is a top perspective view of an aerosol delivery device showing the new design

FIG. 2 is a front elevational view of the embodiment of FIG. 1;

FIG. 3 is a rear elevational view of the embodiment of FIG. 1;

FIG. 4 is a left side elevational view of the embodiment of FIG. 1;

FIG. 5 is a right side elevational view of the embodiment of FIG. 1;

FIG. 6 is top plan view of the embodiment of FIG. 1; and, FIG. 7 is a bottom plan view of the embodiment of FIG. 1. The broken lines in the drawings depict portions of the aerosol delivery device that form no part of the claimed design.
